[57] ABSTRACT

An air cooled steam condenser having plates mounted within the condensate outlet header compartment. The plates in effect form a series of subchambers, each of which communicate with a row of cooling tubes in which steam is condensed by a stream of cooling air flowing over, around and past the tubes. The rows of tubes extend transversely of the direction of airflow and the rows extend perpendicular to the direction of airflow at spaced intervals. Tube sleeves extend through a plurality of openings in the outlet header into the header compartment and terminate, each in a separate subchamber. Valves are connected in condensate lines extending from the tube sleeves externally of the header compartment. The valves are adjusted so that the passages through the valves are smaller in area for each successive connected subchamber in the header into which the condensate flows so that only that amount of steam that can be condensed effectively within the tubes in any row, enters such row due to the back pressures created by the varying sizes of valve openings, having regard to the length and the temperature difference at the particular row which determines the cooling effect of the airflow over the successive rows of tubes.

STEAM CONDENSER CONSTRUCTION

CROSS REFERENCE TO RELATED APPLICATIONS

The steam condenser construction is an improvement upon the constructions shown, described and claimed in the copending application of Kenneth B. Ris, filed Mar. 19, 1971, Ser. No. 126,174, and the copending application of Kenneth B. Ris and myself, filed May 3, 1971, Ser. No. 139,371.

BACKGROUND OF THE INVENTION

Field of the Invention

The invention relates to heat exchangers and in particular to air cooled steam condensers. More particularly the invention relates to control means mounted within the condenser outlet header and adjusted externally of the header whereby the amounts of steam entering various rows of condensing tubes are metered or reduced proportionally to the reduced cooling effect of the cooling air due to increased cooling air temperature resulting from heat extracted from tubes previously cooled, so that only that amount of steam that can be cooled efficiently is supplied to the tubes of a particular row.

Description of the Prior Art

Air cooled steam condensers usually include a plurality of condenser tubes arranged in rows one behind the other in the direction of airflow of the cooling air. Steam enters the condenser inlet header which communicates with the inlet ends of the tubes and then flows through the tubes wherein it is condensed. Fans blow cooling air across the tubes in an airflow direction generally perpendicular to the rows of tubes. The steam is condensed by the cooling air to form condensate as it travels through the tubes, and the condensate is collected at the outlet ends of the tubes in any suitable manner. Condensation should take place throughout the length of the tubes for most efficient condenser operation.

Problems have arisen in the construction and operation of air cooled steam condensers as described in U.S. Pat. No. 3,073,575 relating to inefficient steam feed distribution to the cooling tubes, temperature differential changes due to changing weather conditions, etc. The various solutions to such problems suggested in said U.S. Pat. No. 3,073,575, however, are complicated in structure and expensive in execution.

These problems have been eliminated by the constructions shown in said copending applications, Ser. Nos. 126,174 and 139,371, wherein fixed and adjustable partition plates are mounted within the condenser inlet header that meter the amounts of steam entering the various rows of condensing tubes by forming inlet passages and subchambers.

The adjustable partition plates described in said application, Ser. No. 139,371 provide means for selective adjustment of the steam distribution pattern in order to achieve optimum operating conditions at the time of initial installation, as well as to compensate for seasonal changes or for changes in steam supply factors.

However, adjustment of such plates either requires the condenser to be taken out of operation so that the inlet end coverplate can be removed for adjustment of the internal partition plates, or else requires loosening a plurality of lock nuts for manual movement of adjust-

ing rods which extend through the end wall and are attached to the partition plates. Although these adjustment means achieve the intended purpose and solve the above mentioned problems, they are time-consuming and may require the condenser to be shut down for adjustment.

The partition plates forming the steam passages of varying widths in the said copending applications, are shown located within the condenser inlet header. This results in a steam pressure loss during movement of the steam through the inlet header before the steam enters the condenser tubes. This reduced pressure results in reduced heat transfer through the tubes into the cooling air flow.

Accordingly, it is desirable to provide a condenser construction with some means for externally selectively adjusting the steam distribution pattern for providing optimum operating conditions in the condenser, preferably in the condenser outlet header, so that adjustments can be made easily and conveniently without shut down and while the condenser is in operation.

SUMMARY OF THE INVENTION

Objectives of the invention include providing a steam condenser construction having adjustable valve means which meter the amounts of steam flowing through the cooling tubes in tube rows of the condenser, proportional to the condensing ability of the tubes in any particular tube row; providing a steam condenser construction in which the condenser tubes all have the same length, passage cross section, number of fins, and total heat exchange surface area; providing a steam condenser construction in which plates forming subchambers are mounted within the condenser outlet header for selective distribution of steam; providing a steam condenser construction permitting existing condenser designs to be converted easily and inexpensively to establish adjustable metered distribution of steam to the several rows of cooling tubes in the condenser; providing a steam condenser construction in which the metered distribution of steam may be varied easily and conveniently as condenser design factors vary to insure optimum efficiency in condenser operation; providing a steam condenser construction in which the steam flow pattern may be varied by usual valves mounted externally of the condenser outlet header in the condensate drain lines, which communicate with the condensate outlet subchambers; providing a steam condenser construction in which the steam flow pattern may be varied easily and conveniently even while the condenser is in operation; and providing a steam condenser construction which eliminates difficulties heretofore encountered, achieves the stated objectives simply and effectively, and solves problems and satisfy existing needs.

These objectives and advantages are obtained by the steam condenser construction the general nature of which may be stated as including a plurality of tubes arranged in a plurality of generally parallel rows, extending between and communicating with a steam inlet header and a condensate outlet header; the rows of tubes extending transversely of and at spaced intervals perpendicular to the direction of airflow of cooling air that passes over and around the rows of tubes to condense steam flowing through the tubes from the inlet to the outlet header; the condensate outlet header having a chamber and partition means mounted within the

chamber dividing the chamber into a plurality of sub-chambers; the subchambers communicating with at least one row of tubes; separate condensate drain means communicating with each of the subchambers and extending externally from the outlet header chamber; valve means connected with each drain means; control means for the valve means located externally of the outlet header chamber whereby the valve means may be individually adjusted by the control means to create back pressures in the corresponding rows of tubes to regulate the flow of inlet steam in successively smaller amounts to each successive row of said tubes corresponding to the reduced cooling effect of the airflow of cooling air passing successively over the spaced rows, so that the steam flow in each row of tubes may be maintained at an optimum operating level by such adjustment to compensate for changes in operating conditions; and the partition means including a plurality of plates mounted on and extending between the outlet header tubesheet and side wall.

BRIEF DESCRIPTION OF THE DRAWINGS

Preferred embodiments of the invention — illustrative of the best modes in which applicant has contemplated applying the principles — are set forth in the following description and shown in the drawings and are particularly and distinctly pointed out and set forth in the appended claims.

FIG. 1 is a perspective view, with portions broken away, showing an air cooled steam condenser equipped with the improved steam control system;

FIG. 2 is a diagrammatic front elevation of the steam condenser shown in FIG. 1;

FIG. 3 is an enlarged fragmentary top plan view, with portions broken away and in section, looking in the direction of arrows 3—3, FIG. 2 and showing one condenser section;

FIG. 4 is a sectional view taken on line 4—4, FIG. 3;

FIG. 5 is an enlarged sectional view taken on line 5—5, FIG. 4;

FIG. 6 is a further enlarged fragmentary sectional view taken on line 6—6, FIG. 5; and

FIG. 7 is a reduced fragmentary sectional view similar to FIG. 5 showing a modified steam condenser construction. Similar numerals refer to similar parts throughout the drawings.

DESCRIPTION OF PREFERRED EMBODIMENTS

First Embodiment

A typical air cooled heat exchanger is indicated at 1, (FIGS. 1 and 2) and includes two steam condenser sections 2 and 3 supported on frame members 4 and having side and end panels 5 mounted on the frame members 4. Fans 6 mounted on pedestals 7 beneath condenser sections 2 and 3 blow cooling air (indicated by arrows A, FIG. 2) upward through sections 2 and 3.

Steam inlet pipes 8 communicate with a source of steam, such as the exhaust of a steam turbine, to be condensed, and form steam inlets for the individual sections 2 and 3. Condensate outlet lines 9 are connected to the opposite ends of sections 2 and 3 and deliver condensate into a main condensate line 10.

Different heat exchanger installations may have a different number of heat condenser sections 2 and 3 assembled together. The operation and construction of condenser sections each having the improved steam flow control means incorporated therein are similar.

Therefore only one condenser section 2 (FIGS. 3—6) is described in detail.

Condenser section 2 includes a plurality of cooling tubes 11 preferably having helical fins 12 extending outward therefrom. Tubes 11 are mounted within a frame 13 having side channels 14, an inlet header 15 and an outlet header 16.

Tubes 11 are mounted parallel to each other within frame 13 in a plurality of rows 17, 18, 19 and 20 spaced one above the other (FIGS. 4, 5 and 6) arranged in order along the direction of air flow indicated by the arrow A. Tubes 11 in a particular row may be spaced intermediate the tubes in the adjacent rows, above and below, as shown in FIG. 5. Likewise, tubes 11 are assembled within frame 13 so as to have a slight incline from inlet header 15 to outlet header 16 so that condensate flows or drains into header 16.

Outlet header 16 may have a welded construction as shown in U.S. Pat. No. 3,582,599 of Melvin Yohn.

Such construction may include a generally rectangular cross-section formed by top and bottom walls 21 and 22, tubesheet 23, side wall 24, and end walls 25. The outlet ends of tubes 11 are connected in a usual manner by expanding or welding in tubesheet 23; and holes 26 in wall 24 aligned with tubes 11 permit access into header 16 and tubes 11 for cleaning and for removing any obstructions that may form in tubes 11.

Steam inlet header 15 (FIGS. 3 and 4) may be constructed similar to header 16 having aligned holes 27 and 28 formed in tubesheet 29 and side wall 30 for connection with the inlet ends of tubes 11 and insertion of removable plugs 31, respectively. Steam inlet opening 32 in top wall 33 of header 15 is connected by flange coupling 34 with coupling 35 on steam inlet line 8.

In accordance with the invention a plurality of partition plates 36, 37 and 38 are mounted within header 16 between tubesheet 23 and side wall 24 by welds 39. The plates 36, 37 and 38 preferably are parallel to each other and to bottom wall 22, and are mounted between tube rows 17 and 18, 18 and 19, 19 and 20, respectively. Thus, subchambers 40, 41, 42 and 43 are formed within header 16.

Tube sleeves 45, 46 and 47 extend through a plurality of spaced openings 48 in bottom wall 22 into the compartment of header 16 and communicate with subchambers 41, 42 and 43, respectively, as shown in FIG. 5. No tube sleeve is required for communication with subchamber 40 since its respective outlet line 9 can communicate directly through an opening 48 with subchamber 40.

Tube sleeve 45 extends through subchamber 40 and terminates in an opening 49 in plate 36; tube sleeve 46 extends through subchamber 40, through an opening 50 formed in plate 36, through subchamber 41 and terminates in an opening 51 formed in plate 37; and tube sleeve 47 extends through subchamber 40, through a third opening 52 formed in plate 36, through subchamber 41, through a second opening 53 formed in plate 37, through subchamber 42 and terminates in an opening 54 formed in plate 38.

Tube sleeves 45—47 preferably are removably mounted in outlet header 16 to enable access through side wall holes 26 to those tubes 11, shown in dashed lines, FIG. 5, located behind the tube sleeves for removing any obstructions that may form in these tubes. Therefore, a slidably fit is provided between the tube sleeves and bottom wall 22 and plates 36—38 at open-

ings 48 and the various plate openings through which sleeves 45-47 extend. Sleeves 45-47 may be held in position by clamping an outwardly extending annular flange 55 (FIG. 6) formed at the lower end of each tube sleeve between a pair of usual couplings 56 and 57.

Flange couplings 56 surround bottom wall openings 48 and may be welded at 58 to header bottom wall 22. Couplings 57 are welded at 59 to the ends of condensate outlet lines 9 and may be clamped to couplings 56 by bolts 60. A pair of gaskets 61 preferably is placed between those couplings 56 and 57 which clamp a tube sleeve annular flange 55 therebetween, and the respective tube sleeve flange 55 to provide an air and liquid tight connection.

Thus, tube sleeves 45-47 may be removed easily by unclamping couplings 56 and 57 by removal of bolts 60, and then freely sliding the tube sleeve from within header 16 through bottom wall opening 48.

The small amount of condensate and uncondensed steam that may leak between the subchambers through the slidably fit openings between the sleeves and partition plates is insignificant and does not affect the condenser operation.

The adjustment means for varying the amounts of steam entering tube rows 17-20 is provided by valves 62, 63, 64 and 65 which are installed in the condensate lines 9 communicating with subchambers 40, 41, 42 and 43, respectively.

Valves 62-65 are of a usual construction such as a gate or butterfly valve, and are placed in each condensate line 9 between condensate drain openings 48 and main condensate drain line 10. Valves 62-65 in accordance with the invention are located externally of header 16 and are readily accessible for regulation of their internal valve opening, as by simple movement of control crank valve wheels 66.

Steam flow, indicated by arrow B (FIG. 4), enters header 15 through distribution pipe 8 and inlet opening 32. The amounts of steam B_1 , B_2 , B_3 , and B_4 that enter tube rows 17, 18, 19 and 20, respectively, are individually controlled and regulated by valves 62, 63, 64 and 65, respectively, and crank wheels 66. In effect four individual and separate steam and condensate paths are formed in condenser section 2. Each path consists of a row of cooling tubes, a condensate subchamber, a condensate outlet line and a control valve.

Back pressure is created in each of the individual paths by valves 62-65, the amounts of which depend upon the size of valve openings regulated by crank wheels 66. The smaller the valve opening, the greater will be the back pressure, and correspondingly smaller will be the amount of steam entering the particular row of tubes which communicates with the respective subchamber and connected valve.

Valves 62-65 are adjusted so that the valve 62 has the largest opening, valve 63 the next largest opening, valve 64 the third largest opening and valve 65 the smallest opening. Therefore, a larger amount of steam B_1 enters the tubes in row 17 for condensation therein than the reduced amount of steam B_2 entering tube row 18 and likewise the further reduced amounts of steam B_3 and B_4 entering tube rows 19 and 20. This continual reduction in amounts of steam entering succeeding tube rows of similar tubes spaced along the direction of flow A of the cooling air, compensates for the continual increase in temperature of the cooling air and the decreasing mean effective temperature difference as the

air passes from row 17 over the subsequent rows 18-20 picking up heat from the previously cooled rows of tubes.

The sizes of the valve openings are determined by adjusting valve wheels 66 in any particular installation, taking into consideration factors including the pressure and temperature of the steam entering header 15, the velocity and temperature of cooling air flowing at A past the tubes 11, and the total finned heat exchange 10 cooling surface of tubes 11. Ideally, the sizes of the valve openings will be such that the amounts of steam B_1 - B_4 entering the respective rows 17-20 of tubes 11 will be completely condensed as steam flow in any tube 11 reaches the outlet header 16. In actual operation the mixture entering outlet header 16 may consist of 90 percent condensate and approximately 10 percent steam.

Thus, in the event that any of these above design factors change, valve wheels 66 may be adjusted accordingly to admit more or less steam B_1 - B_4 through tube rows 17-20 for condensation within tubes 11. For example the sizes of the valve openings may be increased in winter months in cold weather regions due to the increased cooling ability of the cooling air. Likewise, should the pressure or temperature of the steam entering header 15 change due to a change in operating conditions of the source of steam supply, the valve openings may be adjusted accordingly to enable maximum efficiency to be achieved in the operation of the condenser.

Thus, any individual row of tubes receives only that amount of steam that can be condensed throughout its length, eliminating premature or insufficient condensation within the tubes, while using tubes all identically the same in the construction of the condenser. The valve means may be adjusted easily and conveniently permitting more or less amounts of steam to flow into the various tube rows, so that as the factors which effect the condensation rate within the tubes change, the supply of steam to the tubes can be changed to enable the condenser to operate at optimum efficiency.

The improved external adjustment and control means for individually varying the amounts of steam to the tube rows permits ease of adjustability heretofore unattainable. Such ease in adjustment enables the steam flow pattern to be changed continually to match any change in those factors which affect the rate of condensation.

This constitutes an important improvement over the adjustable partition plates of said copending application, Ser. No. 139,371 which either requires shutting down the condenser for removal of the header cover-plate for manual adjustment of internal partition plates, or else requires the movement of the internal partition plates by means of externally extending adjustment rods. Either means of adjustment required a considerable amount of time in comparison with the simple movement of valve crank wheels 66 of valves 62-65.

Valve 62 which is located in the drain line 9 which communicates with subchamber 40 may be eliminated in many condenser installations. Such elimination is possible since tube row 17 which communicates with subchamber 40 is cooled first by the air flow, before the air flow temperature is increased by heat transfer from flowing past subsequent tube rows and can be more uniformly controlled.

Thus, the openings in valves 63, 64 and 65 can be varied so as to enable the proper amounts of steam to flow through tube rows 18, 19 and 20 with the remaining amounts flowing through rows 17. In those installations where valve 62 is eliminated, the size of condensate line 9 communicating with subchamber 40 must be predetermined by proper calculations based upon the average value of the factors effecting the condensation rate and the adjustability provided by valves 63-65.

Second Embodiment

A modified construction of the improved steam condenser construction is shown in FIG. 7 in which only a single partition plate 67 is mounted within the condensate outlet header 68 dividing it into subchambers 69 and 70.

Each subchamber communicates with two rows of cooling tubes instead of one, as in condenser section 2 where a single row of tubes communicates with each subchamber.

The header bottom wall 71 is formed with two spaced openings 72 and 73. A tube sleeve 74, similar to tube sleeve 45-47, extends through opening 73 and subchamber 69, and communicates with subchamber 70 through an opening 75 formed in plate 67.

Control valves (not shown) are placed in the two condensate drain lines 9 in a manner similar to valves 62-65 for varying the amounts of steam entering the tube rows.

IN GENERAL

Accordingly, the improved steam condenser construction provides for progressively reducing the amount of steam passing through the rows of tubes in the path of flow of cooling air; enables condenser tubes having the same length, the same passage cross section, the same number of fins and the same total heat exchange surface to be used in fabricating the condenser; enables many designs of steam condensers to be easily and inexpensively converted to the improved steam condenser construction; enables the amounts of steam that enter the various rows of tubes to be adjusted easily and conveniently, externally of the condenser so that if those factors which affect the rate of condensation are changed, then the amounts of steam to be condensed may be adjusted accordingly to provide maximum efficiency in the operation of the condenser; prevents premature condensation which may result in frozen conditions during cold weather; provides a means of adjusting the steam flow to the various rows of tubes without requiring the condenser to be out of operation; and provides such a construction which is effective, safe, inexpensive, and efficient in assembly, operation and use, and which achieves all the enumerated objectives, provides for eliminating difficulties encountered with prior devices, and solves problems and obtains new results in the art.

In the foregoing description, certain terms have been used for brevity, clearness and understanding but no unnecessary limitations are to be implied therefrom beyond the requirements of the prior art, because such terms are used for descriptive purposes and are intended to be broadly construed.

Moreover, the description and illustration of the invention is by way of example, and the scope of the invention is not limited to the exact details of the construction shown or described.

Having now described the features, discoveries and principles of the invention, the manner in which the improved steam condenser construction is constructed, assembled and operated, the characteristics of the new construction, and the advantageous, new and useful structures, devices, elements, arrangements, parts, and combinations are set forth in the appended claims.

I claim:

1. In a steam condenser of a type in which a plurality of tubes are arranged in a plurality of generally parallel rows, extending between and communicating with a steam inlet header and a condensate outlet header; in which the rows of tubes extend transversely of and at spaced intervals perpendicular to the direction of airflow of cooling air that passes over and around the rows of tubes to condense steam flowing through the tubes from the inlet header to the outlet header; and in which all of the tubes in all of the rows have the same internal diameter and length and the same heat exchange cooling surface area; the condensate outlet header having partition means mounted within the header dividing the header into a plurality of subchambers; the subchambers each communicating with at least one row of tubes; separate condensate drain means for and communicating with each of said subchambers and extending externally from the outlet header; a plurality of the drain means including valve means; and the valve means each including control means located externally of the outlet header be individually adjusting the flow therethrough so as to create back pressures in the corresponding rows of tubes and thereby regulate the flow of inlet steam in successively smaller amounts to each successive row of said tubes corresponding to the reduced cooling capacity of the airflow of cooling air passing successively over the spaced rows so that the steam flow in each row of tubes may be maintained at an optimum operating level by such adjustment to compensate for changes in operating conditions.
2. The construction defined in claim 1 in which the outlet header includes a tubesheet and side wall; in which the partition means includes a plurality of partition plates; and in which the partition plates are mounted on and extend between said tubesheet and side wall.
3. The construction defined in claim 2 in which the outlet header includes a bottom wall; in which said bottom wall is formed with a plurality of openings; in which the partition plates are each formed with at least one opening, in which the partition plate openings are aligned with said bottom wall openings; in which a plurality of the drain means includes tube sleeves; and in which said tube sleeves extend through the aligned bottom wall and partition plate openings for communication with the outlet header subchambers.
4. The construction defined in claim 3 in which the tube sleeves are removably mounted on the outlet header.
5. The construction defined in claim 3 in which the tube sleeves have slideable fits between the header bottom wall and partition plates at the tube sleeves extensions through the openings formed in said bottom wall and partition plates.
6. The construction defined in claim 3 in which a plurality of flange couplings are mounted on the outlet header bottom wall; in which each of the bottom wall openings is surrounded by one of said couplings; and in

which the tube sleeves slidably extend through said couplings into the outlet header.

7. The construction defined in claim 6 in which each tube sleeve is formed with an outwardly extending annular flange on the tube sleeve end external of the outlet header; in which the drain means each includes a drain line having a coupling attached on one end of said drain line; and in which said sleeves annular flanges are clamped between said drain line couplings and the header bottom wall couplings.

10

8. The construction defined in claim 1 in which the drain means includes a plurality of tube sleeves; in which the tube sleeves each communicate with a separate subchamber and extend externally from the outlet header; in which a drain line is detachably connected to and extends from the external end of each tube sleeve; and in which the valve means and valve control means are connected with said drain lines.
